DESIGN FOR AN ALBUM HOLDER

Robert P. Henn, Cleveland, Ohio

Application July 3, 1947, Serial No. 140,086

Term of patent 14 years

(Cl. D33—2)

To all whom it may concern:

Be it known that I, Robert P. Henn, a citizen of the United States, residing at Cleveland, in the county of Cuyahoga and State of Ohio, have invented a new, original, and ornamental Design for Album Holder, of which the following is a specification, reference being had to the accompanying drawing, forming a part thereof, in which:

Fig. 1 is a perspective view of the album holder embodying my new design.

Fig. 2 is a plan view thereof, and

Fig. 3 is a side elevational view thereof.

I claim:

The ornamental design for an album holder, as shown.

ROBERT P. HENN.
